ATTORNEY.

UNITED STATES PATENT OFFICE

133,969

DESIGN FOR ULTRAVIOLET LAMP

Thomas S. Warren, Los Angeles, Calif.

Application July 13, 1942, Serial No. 107,519

Term of patent 7 years

To all whom it may concern:

Be it known that I, Thomas S. Warren, a citizen of the United States, residing at 928 North Kingsley Drive, Los Angeles, California, have invented a new, original, and ornamental Design for an Ultra Violet Lamp, of which the following is a specification, reference being had to the accompanying drawing, forming part thereof.

Referring to the drawing:

Figure 1 is a perspective view of an ultra violet lamp, showing my new design;

Figure 2 is a side elevation thereof; and

Figure 3 is a top plan view of the lamp.

I claim:

The ornamental design for an ultra violet lamp, as shown.

THOMAS S. WARREN.
